UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed November 18, 1924. Serial No. 750,591.

This invention aims to provide an improved separable fastener.

In the drawings, which illustrate a preferred form of my invention:—

5 Figure 1 is a front elevation of the fastener device;

Fig. 2 is a section on the line 2—2 of Fig. 1;

10 Fig. 3 is a section on the line 3—3 of Fig. 1, showing the socket member of the fastener in cross-section;

Fig. 4 is a section on the line 4—4 of Fig. 3, being partly in elevation;

15 Fig. 5 is a top plan view of the socket; and

Fig. 6 is a bottom plan view of the socket.

Referring to the drawings, I have shown a stud including a head 1, neck 2 and a 20 base 3 secured to the stud-carrying fabric 4 by the usual rivet 5 and cooperating with a socket secured to the socket-carrying fabric 6 by the attaching prongs 7 which penetrate the socket-carrying fabric 6 and are clenched 25 within the usual socket-securing cap 8. It will be understood that, while I have referred to the socket and stud-carrying fabric, any suitable flexible material may be used.

30 The socket proper includes the casing 9 containing a spring 10 of the type presenting generally parallel resilient end portions or jaws 11 for engagement with the neck 2 of the stud and resilient reverse bends connecting these ends with an integral support 12 adjacent the periphery of the casing 9. The socket also includes a casing closure plate 13 secured to the casing by, bending inwardly, a portion of the upstanding marginal portion of the casing, as illustrated in 35 Figs. 3 and 5.

The attaching prongs 7 are presented by the closure plate 13, which is supported by two upstanding projections 14, 14 pressed 40 from the face of the socket, as illustrated, thereby spacing the closure plate from the face of the casing so as not to interfere with the movement of the resilient parts of the spring, as illustrated in Figs. 2, 3 and 4; and 45 also to support the closure plate when the prongs 7 are clenched into engagement with the cap 8.

The socket also presents a stud-receiving aperture 15 to admit the head 1 of the stud 50 between the jaws 11 so that they may engage

the neck 2 of the stud. This aperture is extended by two notches 16, 16 which extend from the aperture on a diametrical line parallel with the jaws and provide a lateral lock against separation of the fastener by a 60 strain exerted in the direction of either of the notches.

The projections 14, 14 are located at the outer ends of the notches (Figs. 4 and 5) and are formed from the material which is 65 pressed from the face of the casing to provide the notches 16, 16. Thus the projections are integral with the casing and the spring 10 may be positioned relative to the notches in the casing by either of the projections before the closure plate is secured to the casing, whereas, if the projections are located on the closure plate, the closure plate must be positioned relative to the 70 spring and the spring must be positioned in 75 the casing without anything to keep it in position during assembly of the socket proper. In my invention, however, as illustrated, the spring may be placed in the casing and positioned by the projections 14, 14, thus making it unnecessary to position the closure plate relative to the spring or the casing.

In securing the socket to the glove or other flexible material, one of the notches, 80 which are of less width than the diameter of the neck 2 of the stud, should be positioned in the line of strain or toward the adjacent edge of the material. Thus, when 85 stresses are exerted in opposite directions upon the stud and socket, a portion of the neck 2 of the stud will enter one of the notches 16 to provide a lock against the separating strain arising from the resolution of forces when the fastener parts under 90 lateral stress as disclosed in my United States Letters Patent No. 1,513,964, issued November 4, 1924.

While I have shown and described a preferred embodiment of my invention, it will be understood that changes involving omission, substitution, alteration and reversal of parts, and even changes in the mode of operation, may be made without departing from the scope of my invention, which is best defined in the appended claims.

Claims:

1. A separable fastener comprising, in combination, a stud having a head and a neck, a cooperating socket including a cas- 110

ing presenting a stud-receiving aperture therethrough, a spring in said casing presenting stud-engaging portions intersecting said aperture a notch at one side of said aperture of less width than the diameter of the neck of the stud for receiving a portion of the neck of the stud to lock the fastener when under lateral strain in the direction of the notch and a projection 10 pressed from said casing and extending upwardly therefrom at the end of said notch between the stud-engaging portions of said spring, to position them relative to the notch and the stud-receiving aperture.

15 2. A separable fastener comprising, in combination, a stud having a head and a neck, a cooperating socket including a casing presenting a stud-receiving aperture therethrough, a spring in said casing presenting stud-engaging portions intersecting said aperture, a pair of diametrically opposed neck-receiving notches at the periphery of said aperture into one of which a portion of the neck of the stud may be received when the fastener is under lateral strain in the direction of the notches and an upstanding projection pressed from said casing at the end of each notch, one of said projections positioning the neck-engaging 20 portions of said spring relative to said notches.

25 3. A separable fastener comprising, in combination, a stud having a head and a neck, a cooperating socket including a casing presenting a stud-receiving aperture therethrough, a neck-receiving notch at the periphery of said aperture into which only a portion of the neck of the stud may be pulled when the fastener parts are under 30 lateral strain, a projection extending from said casing at the end of said notch, a return bend spring in said casing provided with neck-engaging portions positioned relative to said notch by said projection and a closure plate fitted within the casing and supported by said projection, the marginal flange of said casing being thrown inwardly over said closure plate to secure said closure plate and casing together.

40 4. A separable fastener comprising, in combination, a stud having a head and a neck, a cooperating socket including a casing presenting a stud-receiving aperture therethrough, a pair of diametrically opposed notches at the periphery of said aperture, said notches being of such width that only a portion of the stud may enter when the fastener parts are under lateral stresses, a spring of the return bend type located in 45 said casing, a projection extending from said casing at the end of each notch, one of said projections positioning the neck-engaging portions of the spring relative to said notches and a closure plate presenting a plurality of prongs for attaching said

casing to a support, said closure plate being spaced from said spring by said projections.

5. A separable fastener comprising, in combination, a stud having a head, a neck and a base portion, a cooperating socket including a casing containing a spring presenting generally parallel resilient neck-engaging portions, a stud-receiving aperture in said casing, notches provided at opposite sides of said aperture and located between 50 said neck-engaging portions of the spring, each notch being of such width as to permit only a portion of the neck of the stud to enter when the stud and socket are under lateral stresses, a closure plate presenting a plurality of attaching prongs for securing said casing to a flexible support and a projection extending toward said closure plate from the outer end of each notch, said projections formed from the material struck out 55 to provide said notches and said projections supporting said closure plate and positioning said resilient neck-engaging portions relative to said notches.

6. A separable fastener socket including a casing presenting a stud-receiving aperture therethrough having opposed notches in the wall surrounding the aperture, a spring in said casing presenting a pair of resilient neck-engaging jaws intersecting said aperture, said notches being located between the jaws of said spring and being of less width than the neck of a cooperating stud, thereby to receive only a portion of the neck of the stud when the fastener parts are subjected to lateral stresses, a closure plate secured to said casing and a plurality of projections pressed from the face of said casing at the outer ends of said notches for spacing said closure plate from said spring and for positioning 100 the jaws of said spring relative to said aperture and said notches, said projections providing the only means for spacing said closure plate relative to said casing.

7. A separable fastener socket including a casing presenting a notched aperture therethrough, the notch being of less width than the diameter of the neck of a cooperating stud, thereby to receive only a portion of the neck of the stud when the fastener parts are subjected to lateral stresses, a spring in said casing presenting a pair of resilient neck-engaging jaws intersecting said aperture, a closure plate secured to said casing and closure plate supporting and spring-positioning projections pressed from the front face of said casing.

8. A separable fastener comprising, in combination, a stud secured to a stud-carrying medium, a cooperating socket secured to a socket-carrying medium, said socket providing a casing having a stud-receiving aperture, a spring located in said casing and presenting jaw portions intersecting said aperture, a notch of less width than the di-

ameter of the neck of the stud at that side of said aperture adjacent the free edge of the socket-carrying medium to receive only a portion of the neck of a stud when the 5 fastener parts are subjected to lateral stresses thereby to prevent separation of said stud and socket by lateral stresses exerted to pull

the neck of the stud into the notch and a projection formed from the metal struck out to provide said notch, said projection positioned 10 said spring jaws relative to said notch.

In testimony whereof, I have signed my name to this specification.

FRED S. CARR.
